Primary Examiner — Sandra S Snapp*Assistant Examiner* — Katherine Glennon(74) *Attorney, Agent, or Firm* — Abelman, Frayne & Schwab(57) **CLAIM**

The ornamental design for a watchcase, as shown and described.

DESCRIPTION

FIG. 1 is a front right perspective view of a watchcase showing my new design;

FIG. 2 is a rear left perspective view thereof;

FIG. 3 is a front view thereof;

FIG. 4 is a rear view thereof;

FIG. 5 is a left side view thereof;

FIG. 6 is a right side view thereof;

FIG. 7 is a bottom view thereof; and,

FIG. 8 is a top view thereof.

The portions of the watchcase shown in broken lines form no part of the claimed design. The word "RAILMASTER" that appears on the back of the watch, and the Greek letter "Omega" that appears on the back of the watch and the watch crown, are both registered trademarks of the Applicant, OMEGA SA (OMEGA AG) (OMEGA LTD.).
